UNITED STATES PATENT OFFICE.

CHARLES J. REILLY, OF SYRACUSE, INDIANA, AND SPENCER B. NEWBERRY, OF SANDUSKY, OHIO, ASSIGNEES TO THE SANDUSKY PORTLAND CEMENT COMPANY, OF SANDUSKY, OHIO, A CORPORATION OF WEST VIRGINIA.

APPARATUS FOR DIGGING, TREATING, AND DELIVERING MARL.

SPECIFICATION forming part of Letters Patent No. 699,974, dated May 13, 1902.

Application filed July 20, 1901. Serial No. 69,078. (No model.)

To all whom it may concern:

Be it known that we, CHARLES J. REILLY, residing at Syracuse, in the county of Kosciusko and State of Indiana, and SPENCER B. NEWBERRY, residing at Sandusky, Erie county, Ohio, citizens of the United States, have invented a certain new and useful Improvement in Apparatus for Digging and Treating Marl and Delivering it into Receivers, of which the following is a full, clear, and exact description, reference being had to the accompanying drawings.

Much of the marl used in the manufacture of Portland cement is found in deposits of greater or less thickness on the bottom of lakes. This marl is dredged and carried ashore and into the factory, where after the different small batches have been chemically analyzed the other ingredients are added in proper proportions, determined by such analyses.

The object of this invention is to economically get the marl from the bottom of the lake and deliver it to the factory on shore in the best condition for determining at minimum expense what other ingredients and how much thereof must be mixed with said marl to make the desired cement mixture.

The invention consists in the construction and combination of parts, hereinafter described, and pointed out definitely in the claims.

Referring to the drawings, Figure 1 is a side elevation of the entire apparatus. Fig. 2 is a plan view thereof. Fig. 3 is an enlarged side elevation, partly in section, of a portion of a boat and the mechanism which it carries. Fig. 4 is a plan view, partly broken away, of the same mechanism which is shown in Fig. 3. Fig. 5 is a diagrammatic view of the pipe and valve system associated with the two tanks. Fig. 6 is a side elevation of a part of the same pipe and valve system. Fig. 7 is an end view thereof. Fig. 8 is a plan view thereof, and Fig. 9 is a sectional end view thereof.

Referring to the parts by letters, A represents a boat, preferably a flat-bottom scow-like structure. It carries, among other things, a dredging apparatus, preferably a continuous

bucket-dredge B. There is nothing new in this bucket-dredge in itself, either in respect to its construction or the mechanism for operating it. Wherefore it is not thought necessary to describe it further than to say that its buckets b are adapted to dig the marl from the bottom of the lake and to carry the same to an elevated position and to discharge it into a chute C, through which it falls into a pug-mill D. This pug-mill may be of any suitable construction capable of disintegrating the lumps of marl and of mixing the disintegrated marl with water to make a thin homogeneous mud or slurry. Connected with the discharge end of the pug-mill is a hopper E, having two branch pipes e e', which severally discharge into two stout air-tight metal tanks F F', arranged side by side in the bottom of the boat. These tanks have discharge-pipes H H', whose outer ends are connected with a flexible pipe J, which extends to the shore. The inner ends of these pipes extend into said tanks and are turned downward, and their open lower ends are in slight depressions f' in the bottoms of the said tanks. By this construction substantially all of the contents of the tanks can be discharged through these pipes by the method to be explained. This flexible pipe J is made of sections j, connected by flexible joints j', and the whole flexible discharge-pipe is supported by floats K, connected thereto at suitable intervals. The shore end of this flexible pipe is fixed and is connected with a branched pipe M, whose branches m have valves m' and are adapted to severally discharge into tanks N N'. On the boat is also an air-compressor G, of any suitable form. It (or a compressed-air accumulator) is connected with the tanks F F' by pipes g g', in which are valves g' g''. There are also valves h h' in the discharge-pipes H H' and valves e' e' in the inlet-pipes e e'. While these several valves may be of any suitable construction and may be operated by any suitable means, we prefer to employ the construction and operating mechanism shown in the drawings, and particularly in Fig. 5. Each of the valves h h' e' e' is a slide-valve and is connected with a piston r, which is movable in a fixed cylinder R. Two com-

pressed-air pipes $r' r^2$ are connected with each of said cylinders, the one behind and the other in front of its said piston. This construction is clearly shown in connection with the valve h at the left side of Fig. 5. A main pipe Q from the air-compressor or its equivalent is provided with as many branches q as there are valves to be operated, as described, by compressed air. Each of these branch pipes q is connected with a valve-casing T , and with each of these valve-casings a branch discharge-pipe v is also connected, the several branches v being connected with a main discharge-pipe V , which is open to the atmosphere. An associated pair of air-pipes $r' r^2$ are also connected with each of these valve-casings and lead therefrom to a cylinder R , as before specified. In each valve-casing is a valve t , by means of which either one of the pipes $r' r^2$ may be placed in communication with the pipe q , while the other is placed in communication with the pipe v . These several valves t are provided with operating-arms t' , which are all connected with a single operating device t^2 , and the valves are so set that compressed air is admitted into the pipes r' , associated with the valves e^2 and h' , whereby said valves will be closed, and at the same time air is admitted to the pipe r^2 , associated with the valves e^3 and h , whereby said valves will be opened. By the operation of the single operating device t^2 the position of all of these four valves will be reversed.

35 The valves $g^2 g^3$ are severally in valve-casings $g^4 g^5$. The pipe g and a branch q' of the pipe Q and a branch v' of the pipe v are connected with the valve-casing g^4 , while the pipe g' and a branch air-pipe q and a branch discharge-pipe v are connected with the casing g^5 . These valves $g^2 g^3$ are of such construction that when they are in one position air from the pipe q will flow into the corresponding tank, while if they are in another position the air may flow from said tank through the pipe V and thence into the atmosphere.

In the operation of the described mechanism the various valves may be in the position shown in Fig. 5, in which case the thin slurry from the hopper E is flowing through the pipe e' into tank F' , the outlet from said tank being closed by valve h' , and the valve g^3 being in such position that air may freely escape from said tank. At the same time the tank F , having been previously filled, is receiving compressed air (the valve g^2 being properly turned, as shown) the valve e^2 is closed and the valve h in the outlet-pipe H is opened, and therefore the compressed air is forcing the slurry from the tank F through the pipe H and the flexible pipe K to the shore, where it is being received into either of the receiving-tanks desired. When this tank F is emptied and the tank F' is filled, the valve g^2 is first turned to disconnect the tank F from the air-compressor and allow the

air in said tank to escape to the atmosphere. Then the valves t are operated, the result being that the position of several valves $h' h e^2 e^3$ are reversed. Then the valve g^3 is turned to its opposite position, whereby air from the air-compressor is admitted into the tank F' , and thereby the contents of said tank is forced through the pipe H' . The tank F' will at the same time be filled from the hopper E . The contents of each of the tanks before the compressed air is allowed to enter the same is a substantially homogeneous substance. If it is not entirely so, it becomes such in passing through the flexible pipe K to the shore. Each tank full is emptied into a separate receiving-tank in the factory, and therefore an analysis of the contents of each of these receiving-tanks determines what material must be added to the contents of that receiving-tank to make the proper cement mixture.

The boat A may be moved about from time to time as may be necessary, and suitable machinery may be provided for this purpose, although since it constitutes no part of the present invention such machinery is not shown.

The machinery on the boat may be driven by an electric motor W , the conductor-wires for which may be attached to and supported by the flexible pipe K .

Having described our invention, we claim—

1. In combination, a boat, and, supported upon it, dredging mechanism, a pug-mill into which the material raised by the dredge is delivered, two air-tight tanks, valved pipes through which the products of the pug-mill may be delivered into said tanks respectively, a compressed-air apparatus, and valved pipes connecting it with the two tanks respectively, valved discharge-pipes for said tanks, and a flexible pipe connected with said discharge-pipes and extended therefrom to the shore, substantially as and for the purpose specified.

2. In combination, a boat, and, supported upon it, dredging mechanism, a pug-mill into which the material raised by the dredge is delivered, two air-tight tanks, valved pipes through which the products of the pug-mill may be delivered into said tanks respectively, a compressed-air apparatus, and valved pipes connecting it with the two tanks respectively, valved discharge-pipes for said tanks, and a flexible pipe connected with said discharge-pipes and extended therefrom to the shore, a branched pipe to which the shore end of said flexible pipe is connected, valves in said branches, and receiving-tanks into which said branches respectively discharge, substantially as and for the purpose specified.

3. In combination, a boat, and, supported upon it, dredging mechanism, a pug-mill into which the material raised by the dredge is delivered, two air-tight tanks, valved pipes through which the products of the pug-mill may be delivered into said tanks respectively, a compressed-air apparatus, and valved pipes connecting it with the two tanks respectively,

valved discharge-pipes for said tanks, an electric motor and driving mechanism connecting the same with the dredging mechanism, the pug-mill, and the compressed-air apparatus, a flexible pipe, to which both of said discharge-pipes are connected, and which extends to the shore, floats to which said flexible pipe is connected, and conductor-wires supported by said flexible pipe and extending from the shore to the motor on the boat, substantially as and for the purpose specified.

4. In combination, a boat, two air-tight tanks on said boat, each having a valve-controlled inlet-pipe and a valve-controlled outlet-pipe, mechanism for simultaneously operating the valves in all of said inlet and outlet pipes, a flexible pipe connected with said outlet-pipes and extended to the shore, an

air-compressor upon said boat, and two valve-controlled pipes connecting said air-compressor with said tanks respectively, substantially as specified. 20

In testimony whereof we hereunto affix our signatures each in the presence of two witnesses.
